UNITED STATES PATENT OFFICE.

JOHN V. PILCHER, OF LOUISVILLE, KENTUCKY.

DESIGN FOR A MEMBER OF CUFF-HOLDERS.

SPECIFICATION forming part of Design No. 29,727, dated November 29, 1898.

Application filed November 4, 1898. Serial No. 695,512. Term of patent 7 years.

To all whom it may concern:

Be it known that I, JOHN V. PILCHER, a citizen of the United States, residing at Louisville, in the county of Jefferson and State of Kentucky, have invented and produced a new and original Design for a Member of a Cuff-Holder; and I do hereby declare the following to be a full, clear, and exact description of the same, reference being had to the accompanying drawings, forming a part thereof.

Figure 1 of the drawings is a perspective view of a member of a cuff-holder, and Fig. 2 a plan view thereof.

As shown in the drawings, the leading feature of my design consists of the longitudinal bar A, having at its outer extremity the T-shaped arms B, extending from the sides thereof, and a plate C, joining said arms by a right-angle shank a and located above the plane of the arms. The plate C is segmental

in shape and located between the cross-heads b, the cross-heads extending parallel with the bar A, and are joined thereto by the intermediate portions c, which, together with the heads, form the T-shaped arms B. The T-shaped arms B and the bar A are rounded upon their edges, as shown, and the shank a is flat-sided. The longitudinal bar A has its sides in the form of a scroll, as shown at d.

Having now fully described the design, what I claim is—

The design for a member of a cuff-holder, substantially as herein shown and described.

In testimony whereof I affix my signature in presence of two witnesses.

JOHN V. PILCHER.

Witnesses:

VARNUM J. BOWERS,
FRANK G. LENNEBACKER.
